Inventor,

Calvin J. Engle;

Attorney.

UNITED STATES PATENT OFFICE.

CALVIN J. ENGLE, OF PORTLAND, INDIANA.

PUMPING-JACK.

No. 893,909.

Specification of Letters Patent.

Patented July 21, 1908.

Application filed July 20, 1907. Serial No. 384,810.

To all whom it may concern.

Be it known that I, CALVIN J. ENGLE, a citizen of the United States, residing at Portland, in the county of Jay and State of Indiana, have invented a new and useful Pumping-Jack, of which the following is a full and accurate specification, being such as will enable others skilled in the art to which it appertains to make and use the same.

10. My invention relates to a pumping-jack for oil-wells, operating on the principle of a bell-crank, or segmental gear, which is actuated through the medium of a cable or the like which extends therefrom to the source 15 of power, whereby when the cable or the like is drawn endwise in a direction away from the well the polish-rod will be lifted up, and after its highest limit has been reached it will return by gravity to its lowest limit when 20 the cable or the like is released or slackened.

The object of my invention, broadly speaking, is the provision of a pumping-jack which will be strong and durable in construction; easily assembled and placed in operative position; easily disconnected and capable of being packed in a small compass of space; easily operated and controlled; and adapted to afford a high degree of efficiency with a minimum of expense.

30. A further object is to provide a pumping-jack which while light in weight, and comprising a minimum of parts, is adapted to impart to the pumping, or polish, rod an absolute straight-line vertical reciprocatorial motion, which is the desideratum in devices of this character.

More specifically stated my object is to provide a pumping-jack adapted to be connected to the projecting casing of an oil-well, and to provide for quick, easy, secure and adjustable coupling of the device to the 40. polish-rod of the well to be operated on.

Other objects and particular advantages of my invention will be made apparent in the 45 course of the following specification and by an inspection of the accompanying drawings forming a part thereof.

The preferred manner for the construction of my invention is shown in the accompanying drawings, in which—

Figure 1 shows a top plan view of the invention in operative position; Fig. 2 is a side elevation of the same; Fig. 3 is a detail perspective view of the connecting arm; Fig. 4 is an end view of the hub; Fig. 5 is a rear elevation of the jack; and Fig. 6 is a cross

sectional view, as taken on the line $x-x$ of Fig. 2.

Similar indices denote like parts throughout the several views of the drawings. 60

In order that the construction and operation of my invention may be fully comprehended I will now take up the description thereof in concrete detail, in which I will set forth the same as briefly and as compactly 65 as I may and with absolute exactitude.

The letter A designates a portion of a well-casing protruding above the surface of the ground; the letter B denotes the well-tubing or working barrel inside the casing; the letter C denotes the polish-rod which is adapted to operate vertically within the tubing; and the letter D denotes the mud-sill, or sills, or frame, resting on the ground to support the jack as presently set forth. 75

The frame of the jack is formed double, having complementary members on each side, the two sides being spaced apart, as shown in Fig. 5, and it comprises in its construction the rear standards 1 and 2, and the 80 front standards 3 and 4, the two sets of standards thereby forming guide-ways, for the purpose presently appearing.

The standards 1 and 2 are connected by a set of braces 5, 6, 7 and 8, and in like manner 85 the standards 3 and 4 are connected by a set of braces 9, 10, 11 and 12, all of said braces being detachably connected to the standards by appropriate bolts as indicated, certain of which will presently be further referred to in 90 another connection.

On the lower ends of the standards 1 and 2 are formed feet, by which they may be secured to the sill D by the bolts *a* and *b*, and the lower ends (not shown) of the standards 95 3 and 4 may be secured to said sill in like manner.

As will have been noticed, the braces 7 and 11 extend downward at an angle to near the lower ends of the standards 3—4, beyond 100 which they extend horizontally, and together encircling the casing A forming a clamp securable to the casing by the bolts *c* and *d*. The bolt *c* also acting to hold together the standards 3 and 4, at their lower 105 ends, as shown in Fig. 6. Similar to the above are the braces 8 and 12 which extend upwards at an angle to a point some distance above said clamp, that is to about the center vertically of the standards 3—4, beyond 110 which they extend horizontally, and together encircling the casing A forming a

clamp which is adapted to be secured around the casing by the bolts *e* and *f*. The bolt *e* also acting to hold together the standards 3—4 in the position shown in Fig. 6. Said 5 clamps form means for rigidly connecting the frame of the jack at the position desired. The upper ends of the standards 3 and 4 are secured together by the bolt *g*, which bolt also connects thereto the forward ends of the 10 braces 5 and 9.

The numeral 13 denotes the rack-bar, having its rear face provided with cogs, or gear-teeth, with its forward edge expanded forming a head to fit in the T-shaped slot formed 15 by the union of the L-shaped (in cross section) standards 3 and 4 as shown in Fig. 6. Near the upper end of the rack-bar is permanently secured a rigid collar having a forwardly extending brace 14, and above which 20 the rack-bar is formed round in cross section to form a pivot.

The numeral 15 designates the connecting arm which is adapted to rotate horizontally on the said pivot formed on the upper end of 25 the rack-bar and to contact with the upper edge of the collar and the brace 14 as shown. The horizontal projecting portion of the connecting arm 15 is forked to receive therein the polish-rod at that point as shown. Oppositely disposed screws *h* and *k* extend 30 through the forks of the connecting arm to provide means for attaching the connecting arm to the polish-rod as indicated.

Extending transversely of the face of the 35 rack-bar 13 and formed thereinto are two channels which are located some distance apart. These channels do not extend entirely across said face as is indicated in Fig. 6, but there is an abutment left at each side 40 forming bearings. Extending longitudinally through said channels and secured in said abutments are the respective axles *a* and *b*, on which is revolvably mounted the respective rollers *c* and *d*, the former being shown 45 in Fig. 2 and the latter in Fig. 6, said axles and rollers and also the channels therefor are identical with each other. Said rollers are adapted to contact with the inner face or base of the bifurcated channel formed by the 50 front standards 3 and 4, as indicated in Fig. 6, the object being to provide roller bearing for the rack-bar, substantially as indicated.

The numeral 16 relates to the hub (Fig. 4) 55 for the segment-gear 17. Said hub is pivoted to rotate between the upper portions of the standards 1 and 2. Radiating out from the periphery of the hub are four pairs of ears, 16^a, 16^b, 16^c, and 16^d, in which are secured by bolts one end each of the radial 60 arms 18, 19, 20 and 21, respectively. Extending back from the rear face of the segmental gear 17 are three pairs of ears 17^a, 17^b and 17^c in which are secured by bolts the forward ends of the respective arms 18, 19 65 and 20, respectively. The arm 21 projects

upward, when the rack bar is raised to its limit approximately, at right-angles to the arm 19, and it is designated as the operating-arm. The upper end of said operating arm should be coupled to the upper end of the 70 segment-gear by the interposed rod or the like designated by the numeral 22. The arms 18, 19 and 20 are of a length such as to connect the segment gear 17 in operative engagement with the gear of the rack-bar 75 13, while the braces of said frame eventuate to retain the segment-gear from lateral displacement in relation thereto.

The numeral 23 designates a rope or cable attached at one end to the upper portion of 80 the arm 21, the other end leading to power by which it is operable reciprocably.

From the above it is manifest that the jack herein described may be assembled and attached to an oil-well as shown, and that if 85 the rope or cable 23 be drawn back to the position shown that on the release thereof the weight of the polish-rod and the parts thereto attached will eventuate in accomplishing the downward stroke,—that is, the 90 polish-rod will sink down into the well the predetermined length of the stroke. The rope or cable may then be drawn back which, of course, will cause the segmental-gear 17, turning on its hub 16, to carry vertically upward therewith the rack-bar 13, and the latter in turn will lift the polish-rod to its upward 95 limit. These two operations, the upward and the downward strokes of the polish-rod, continuing as long as desired, thereby accomplishing the predominant object of the invention: the pumping of the well. It is also 100 notably apparent that my invention is very easily attached in operative position, and when so attached it will of necessity have a maximum of rigidity; that the device may be 105 easily disconnected from the well; that the adjustment of the connection of the polish-rod may be easily and quickly changed, that while being positive and secure the adjustment is quite flexible; and that the entire device may be disassembled and packed in a 110 comparatively small space.

Claims

1. A pumping-jack having a pair of front 115 standards containing a T-shaped channel formed longitudinally thereof, a rack-bar having a head longitudinally thereof adapted to operate in said channel and corresponding therewith in cross-section, a segment-gear 120 meshing with the rack-bar, a hub for said segment-gear pivoted between the rear standards of the frame, arms connecting said hub and the segment-gear, an operating arm extending up from said hub, a connecting-arm 125 mounted on the upper end of the rack-bar, means for attaching said connecting-arm to a polish-rod, and means for securing said frame to a well casing, all substantially as set forth.

2. A pumping-jack characterized by a pair of front standards containing a T-shaped channel formed therebetween and longitudinally thereof, a rack-bar having a head formed longitudinally thereof and operable in and fitting said channel, a segment-gear meshing with the rack-bar, a hub for said segment-gear, a pair of rear standards between which said hub is pivoted, arms connecting the hub and the segment-gear, braces connecting the front and the rear standards, an operating-arm extending up from said hub, a horizontally rotatable con-

nected-arm mounted on the upper end of the rack-bar, means for attaching the connecting-arm to a polish-rod, and means for securing the frame in position with relation to the well casing. 15

In testimony whereof I have hereunto subscribed my name to this specification in 20 the presence of two witnesses.

CALVIN J. ENGLE.
